Inventor,
George Colvin Kennedy.

UNITED STATES PATENT OFFICE.

GEORGE COLVIN KENNEDY, OF WATERLOO, IOWA.

MARBLE-SHOOTER.

1,302,378.

Specification of Letters Patent. Patented Apr. 29, 1919.

Application filed October 23, 1916, Serial No. 127,263. Renewed July 26, 1918. Serial No. 246,933.

To all whom it may concern:

Be it known that I, GEORGE COLVIN KENNEDY, a citizen of the United States of America, and a resident of Waterloo, Black Hawk county, Iowa, have invented certain new and useful Improvements in Marble Shooters, of which the following is a specification.

My invention relates to improvements in marble shooters, and the object of my improvement is to supply means in such a device adapted to increase the accuracy of propulsion of the marble or projectile therefrom when the latter is delivered.

This invention is an improvement upon the marble shooter for which I have previously filed application for United States Letters-Patent, Serial No. 661, filed January 5, 1915.

The above object I have accomplished by the means which are hereinafter described and claimed, and which are illustrated in the accompanying drawings, in which Figure 1 is a side elevation of my improved marble shooter; Fig. 2 is a central longitudinal section thereof, with dotted lines indicating the position of the plunger head when drawn back under tension preparatory to propelling the marble; Fig. 3 is a horizontal longitudinal section of the forward part of said device; Fig. 4 and Fig. 5 are respectively, front and rear end elevations of said device; Fig. 6 represents the plunger-head as developed on a plane surface, and Fig. 7 is a side elevation of the same when the respective members thereof are bent rearwardly.

Similar numerals of reference denote corresponding parts throughout the several views.

As shown, my improved marble shooter comprises an open-ended cylindrical tube 1 having projecting lateral integral longitudinally spaced projections, in longitudinal alignment, adapted for use as handles 2 and 4, said projections or handles, when the tube 1 is rotated to bring them upwardly, then serving as vertically extending sights. The forward and wider handle 2 has a finger-grip slot 3. The tube or barrel 1, with said projections, is preferably formed by stamping same from a plate of metal, then forming the barrel part into tubular shape, and then clamping or fastening an overlapped part 6 over the part 5, the latter extending between the two projections 2 and 4.

Opposite sides of the barrel 1 have relatively long longitudinal slots or openings 8 of the same form and dimensions whose forward ends are squared and spaced a considerable distance from the forward end of the barrel.

A plunger-head 11 is located within the bearing 1 and movable freely therethrough. Referring to Figs. 6 and 7, said plunger-head 11 is stamped from a flat plate of metal in cruciform shape, having the oppositely directed long rectangular members 9, and at right angles therewith, the short oppositely directed rectangular members 12. A concave circular depression 14 is formed centrally in the forward face of the plunger-head 11. All the members 9 and 12 are then bent rearwardly at right angles to the middle or body-part 11. Openings 7 or any other desired engaging-means are located at opposite sides of the forward end of the barrel 1. The numeral 10 denotes elastic rubber bands, of the endless type, placed on the opposite outer sides of the barrel 1, and secured within said openings 7. The rearwardly directed parts of said bands 10 are passed angularly into the slots 8 under tension, then looped about the short lateral projection or members 12 of the plunger-head 11 and said members then clamped over inwardly toward the rear face of the plunger-head, as shown in said Fig. 3, to securely prevent escape of the bands therefrom. The sides of the plunger-head where the members 12 are bent back to hold the bands 10 are spaced from the adjacent inner wall of the barrel so that the bands which are under tension at all times always engage the squared forward ends of the slots and serve as elastic buffers or stops for the plunger-head when drawn back and then released. The rearwardly directed long members 9 of said plunger-head are located within and close to the inner walls of the upper and lower troughs of the barrel 1 above and below the side openings 8 therein. These members 9 serve as guides for the plunger-head to prevent lateral displacement or

swinging thereof and keep the plunger-head vertical and truly centered within the barrel, as shown by said Figs. 4 and 5.

The marble shooter may be used to effect a dropshot when the handles 2 and 4 are downwardly directed, or may be used for a rolling shot when said handles are vertically directed and employed as longitudinally arranged sights.

10 A marble 13 may be placed within the forward end of the barrel 1 and seated in the concavity 14 of the plunger-head, and then pushed rearwardly with said plunger-head far enough to permit of the marble being 15 grasped between the thumb and a finger of one hand through the oppositely located openings 8. The marble is then pulled rearwardly a sufficient distance, as indicated by dotted lines in said Fig. 2, to place the rubber bands 10 under a requisite degree of tension. When the barrel has been sighted, the marble is simply released by removing said finger and thumb, and is then propelled 20 swiftly and accurately forward by the reaction of the bands 10. It will be seen that since the guide members 9 keep the plunger-head exactly centered and free from lateral swinging movements, the two rubber bands 10 are always under equal tension which insures 25 accuracy in shooting, while the concavity 14 of said plunger-head, properly centers the marble. It will also be observed that the plunger-head 11 is narrower than the diameter of the marble 13, so that when 30 the marble is released by the finger and thumb, the aim is not destroyed by any contact of the plunger-head therewith. The contacts of the inturned parts of the rubber bands with the forward squared ends of the 35 slots causes the bands to act as resilient stops between the plunger-head and the barrel, whereby the projectile is discharged with a sudden delivery or snap, like the smart impulse afforded by the propelling thumb when 40 a marble is projected by hand, thus promoting 45 accuracy in delivery.

It is to be understood that considerable variation may be made in the construction of said plunger-head and propelling means 50 relative to materials, form, dimensions, and arrangement, without departing from the principle of this invention.

Having described my invention, what I

claim as new, and desire to secure by Letters-Patent, is:

55

1. In a device of the character described, a tubular barrel having longitudinal slots in opposite sides, a plunger-head movable longitudinally within said barrel, formed of a body having members directed longitudinally, certain of said members serving as guides to prevent rocking of the plunger-head, the other members serving as engaging-means, and yieldable resilient propelling-means connected between said engaging-means and opposite parts of the said barrel.

2. In a device of the character described, a tubular barrel having longitudinal slots on opposite sides, a plunger-head in said barrel adapted to move therein longitudinally and having side-ears opposite said slots, and elastic-bands connected to the forward end of said barrel on opposite sides in advance of said slots, the bands having loops 75 passed about said ears, and the ears serving to spread the loops apart in front of the plunger-head to admit fingers of the user through the loops into the barrel.

3. In a device of the character described, a tubular barrel having longitudinal slots in its opposite sides, a plunger-head movable longitudinally in said barrel, elastic bands connected to the forward end of the barrel on each side, passed through said slots and 85 connected to opposite sides of said plunger-head, the plunger-head being spaced on the sides from the interior wall of the barrel, the forward ends of said slots being spaced away from the forward end of the barrel 90 enough to keep the elastic bands under tension when the plunger-head is in its forward position, and said bands adapted to engage the forward ends of the walls of said slots after being placed under additional tension 95 and then released to act as resilient stops between the plunger-head and the barrel at the discharge of a projectile by the plunger-head.

Signed at Waterloo, Iowa, this 21st day of 100 October, 1916.

GEORGE COLVIN KENNEDY.
